US00D531798S

(12) **United States Design Patent** (10) **Patent No.:** **US D531,798 S**
(45) **Date of Patent:** **** Nov. 14, 2006**

(54) **REUSABLE RETAIL DISPLAY AND
STORAGE UNIT FOR ELECTRICAL
COMPONENTS**

(75) Inventor: **Scott Andrew Ringo**, Euless, TX (US)

(73) Assignee: **Dobbs-Stanford Corporation**, Dallas, TX (US)

(**) Term: **14 Years**

(21) Appl. No.: **29/227,950**

(22) Filed: **Apr. 15, 2005**

(51) LOC (8) Cl. **03-01**

(52) U.S. Cl. **D3/273; D3/294; D9/415**

(58) **Field of Classification Search** **D3/273, D3/269, 294, 905; D9/415, 423; 206/372, 206/373, 379, 461, 462, 463, 806**
